UNITED STATES PATENT OFFICE

2,508,402

PORTABLE DRILL PRESS

Anton P. Kjérulff, Lake Charles, La.

Application November 7, 1946, Serial No. 708,218

2 Claims. (Cl. 77--7)

1

I have devised an improved tool for hand use in drilling and pressing operations which, being portable, is especially useful to mechanics, such as members of the plumbers' trade, and others who frequently find it necessary to perform work, such as repairs of various kinds, at points distant from their work shop where access may be had to heavy stationary power driven machines.

My invention has for its object to provide a drilling press in which the parts are compact, yet of a size to hold work pieces such as water faucet stems and the like, comprising a frame having upper and lower spaced arms, the former carrying the tool holder and its feed screw while the latter serves as the support or bed to which the work piece is clamped.

In conjunction with a tool of the above described characteristics my invention also comprehends a novel construction of the work piece bed and holder therefor, together with an improved mounting for the parts by which the rotatable tool is adjustable and fed with relation to the work piece.

To these and other ends my invention comprehends further improvements and arrangements of parts all as will be fully described in the accompanying specification, the novel features thereof being set forth in the appended claims.

In the drawings:

Figure 1 is a side elevation of a portable drill press embodying my invention.

Figure 2 is a front elevation thereof.

Figure 3 is a top plan view.

Figure 4 is a bottom plan view.

Figure 5 is a bottom plan view of the tool chuck.

Figure 6 is a detail of the tool rotating handle and the adjacent end of the feed screw therefor illustrating the manner of locking said parts together for performing certain operations.

Figure 7 is a side elevation showing a modified form of work clamp, and,

Figure 8 is a top plan view of the clamping plate shown in Fig. 7.

Similar reference characters in the several figures indicate similar parts.

My description of a portable tool embodying my invention begins with the frame piece, indicated generally by 1, which is U-shape to provide parallel upper and lower arms 2 and 3 which are rectangular in cross section and are stiffened against "springing" under pressure by a reinforcing rib 4, which is disposed centrally around the rear side of the frame. The latter

2

is of a size suitable to be grasped in the hand of a workman and its lower side is flat and unobstructed so that it may be conveniently set upon any foundation as a support and held in engagement therewith for greater convenience during manipulation of the tool elements mounted thereon. The upper arm 2 is split centrally and provided with an opening 5 and extending through the outer ends of the bifurcations thus formed is a clamping screw 6 by means of which they may be drawn together, said screw being provided with an operating handle in the form of a cross bar 7.

The tool carrier mounted on the frame arm 15 2 comprises in part a sleeve 8 which fits the opening 5 in said arm and being clamped therein may be adjusted relatively to the arm 3 of the frame-piece. The upper half of sleeve 8 is threaded to receive a tool feeding member 9, the upper end 20 of which projects beyond the sleeve and is provided with a head or annular enlargement 10 having a knurled edge for convenience in rotating the member 9 to advance or retract it in the sleeve 8. Member 9 is tubular and journaled 25 therein is the drill shaft or spindle 11 having a handle 12 for rotating it, which is secured to the shaft by a cross pin 13. The shaft is prevented from longitudinal movement in the feed member by providing it with a collar 14 bearing 30 against a friction reducing washer 15, which in turn bears against the lower end of member 9 and the placement of a similar washer 16 between the handle 12 and the top of said member. The extended lower end of the drill shaft 35 is threaded as indicated at 17, and carries a tool chuck, the sleeve 18 of which fits within and is guided by the lower end of the sleeve 8. This chuck may be of the well known construction, comprising three jaws for gripping a tool, such 40 as a drill, indicated by 19, upon which the jaws close by rotation of a nut 20.

From the above described assembly of parts it will be seen that the point of a tool secured in the chuck may be brought into engagement 45 with a work piece supported on the arms 3 in the first instance by the vertical adjustment of sleeve 8 and subsequently advanced or retracted by rotation of the feed member, the cutting or drilling action of the tool resulting from its rotation by the handle 12.

In instances where parts of a work-piece are to be separated by pressure, a steel pin is secured in the chuck and forward movement is applied thereto by the rotation of the feed screw. Inasmuch as more power may be required than it

is possible to apply by a person's fingers to the knurled head 10, I provide a simple means for locking it to the handle 12, whereby said parts may be operated conjointly as a unit. To this end the handle 12 and the head 10 are each provided with apertures 25, as shown in Fig. 1, which may be brought into register to receive locking pins 26, as shown in Fig. 6.

The arm 3 of the frame comprises the work bed or holder and for purposes of general serviceability I adapt it to receive a variety of work clamps for holding work pieces lying thereon or which on account of their shape may require them to extend through the bed. To these ends I also bifurcate the arm 3 by providing it with a slot 27 and enlarge this opening at its outer end, as indicated at 28, to about the diameter of the chuck sleeve 18.

In Fig. 4 I have shown a generally useful form of work clamp adapted to hold valve or faucet stems. It comprises two arms 29, 30 having overlapping rear ends connected by a rule joint, the latter being formed by perforating said ends and inserting therein a tubular bushing 31 (see Fig. 1), the extremities of which are expanded to permanently unite the arms. This bushing carries a bolt 32 having a square head 33 which fits the undercut guide 34 of slot 27. A wing nut 35 on the bolt serves to tighten it and hold the clamp in the desired position of adjustment on the work bed. The outer ends of the jaws 29, 30, carry a clamping bolt 35 and between the latter and the rule joint I provide the inner faces of said arms with two jaw portions of different diameters as indicated by 36, 37, the edges of which are serrated, as shown in Fig. 4.

When it is desired to operate on a work-piece which requires holding it in a horizontal position, a clamping plate 40 such as shown in Fig. 7, is employed. This is a flat plate bent down at its rear end 41 and perforated to receive a clamping bolt 42. The forward end of the plate is provided with a slot 43, to accommodate the tool carried in the chuck 18, and upon its lower face, adjacent the inner end of the slot, there is provided a V-shaped notch 44, which facilitates the clamping of a cylindrical work piece, such as indicated by 45 in Fig. 7.

It will be seen from the foregoing description and the accompanying illustrations that I have provided a tool for emergency operations, such as repairing valves and work of a like nature which may be performed by a mechanic at the site of the work. Its general shape and the compactness of the parts renders it as an acceptable adjunct to a mechanic's work kit.

I claim:

1. A portable hand-operated drill press comprising a frame of a size to be conveniently grasped in a workman's hand, having upper and

lower parallel arms, the upper arm being bifurcated and having an aperture for a tool operating mechanism and provided with a clamping screw for drawing said arms together, the lower arm having an upper face forming a bed for a working piece holder and slotted for the accommodation of a securing bolt for such holder, said slot being widened at the outer end of the arm in alignment with the aperture in the upper arm, said holder comprising a pair of arcuate jaws having overlapping rear ends connected by a rule joint, a clamping bolt connecting the forward ends of said jaws for holding a working piece in vertical position, a sleeve adjustably secured in said aperture of the upper arm, a tubular feed screw in the sleeve and a tool spindle journaled in the sleeve.

2. A portable hand-operated drill press comprising a frame of a size to be conveniently grasped in a workman's hand while manipulating the drill press mechanism carried thereon by his other hand, said frame having upper and lower bifurcated arms, the upper arm having an aperture for a tool operating mechanism and provided with a clamping screw for adjustably receiving such mechanism in said aperture, the lower arm having an enlarged opening at its outer extremity centrally alined with the aforesaid aperture and provided with a slot extending rearwardly therefrom, a work-piece clamp mounted on the upper face of the lower arm, said clamp comprising a pair of jaw members having overlapping ends pivotally connected by a rule joint, said jaws being formed with arcuate inner gripping edges, a clamping bolt connecting the forward ends of said jaws and a bolt fitting the slot and cooperating with said clamp to permit its being adjustably secured relative to the enlargement of the arm, a sleeve adjustably secured in the aperture of the upper arm, a tubular feed screw threaded in the sleeve having an adjusting head located above the screw, a tool spindle journaled in the screw and a crosswise handle secured to the outer end of the spindle beyond said screw head.
